Fig. 1.

Fig. 2.

Fig. 3.

Fig. 4.

FIGURE 1 is a front elevational view of a bottle, showing my new design;

FIGURE 2 is a side elevational view taken from the right of FIGURE 1.

FIGURE 3 is a top plan view thereof; and

FIGURE 4 is a bottom perspective view thereof.

The characteristic features of the bottle reside in the constriction below the neck at the juncture with the body to a diameter considerably less than the diameter of the opening of the bottle, and the body of the bottle possessing a bell shaped dome portion adjacent the constriction at the neck having sides which slope inwardly.

I claim:

The ornamental design for a bottle, as shown and described.
